WHEEL COVER OR SIMILAR ARTICLE

George Albert Lyon, Detroit, Mich.

Application January 19, 1953, Serial No. 23,186

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawings:

Figure 1 is a side elevational view of a wheel cover embodying my new design;

Figure 2 is a profile view showing the cross sectional contour of the cover of Figure 1; and

Figure 3 is a fragmentary side perspective view of the cover.

The dotted lines in Figures 1 and 2 showing the conventional tire and wheel assembly are for purpose of illustration only. The dominant feature of my design for the wheel cover resides in those portions thereof shown in full lines.

I claim:

The ornamental design for a wheel cover or similar article, substantially as shown and described.
